UNITED STATES PATENT OFFICE

113,983

DESIGN FOR A COMBINED HOUSE NUMBER ILLUMINATOR AND PLATE

Milton Wishny and Frank C. Gray,
Los Angeles, Calif.

Application August 29, 1938, Serial No. 79,612

Term of patent 3½ years

To all whom it may concern:

Be it known that we, Milton Wishny and Frank C. Gray, citizens of the United States, residing at Los Angeles, in the county of Los Angeles, State of California, have invented a new, original, and ornamental Design for a Combined House Number Illuminator and Plate, of which the following is a specification, reference being had to the accompanying drawing, forming part thereof.

Fig. 1 is a perspective view of the combined house number illuminator and plate showing our new design.

Fig. 2 is an end elevation of the same.

We claim:

The ornamental design for a combined house number illuminator and plate, as shown.

MILTON WISHNY.
FRANK C. GRAY.
